UNITED STATES PATENT OFFICE

WILLIAM JACOB KUNTZ, OF YORK, PENNSYLVANIA

LIME KILN

Application filed January 28, 1930. Serial No. 424,029.

This invention relates to a kiln for the automatic and continued feed and discharge of burning lime.

An object of the invention is the provision 5 of a kiln for burning lime or other materials and more particularly to means for supporting lime or other materials in the kiln, during burning, for facilitating their withdrawal after burning in such a manner as to secure a continuous or nearly continuous flow 10 through a kiln of the vertical or tower type. Another object of the invention is the provision of an improved kiln which will overcome the disadvantages present in kilns of 15 the tower type now in use in which attempts have been made to withdraw the burned material continuously therefrom, the disadvantages arising in large part by reason of the weight of the material in the kiln being 20 supported upon the discharging mechanism.

Another object of the invention is the provision of a kiln having means therein to support the material in and above that part 25 of the kiln where combustion is taking place, said means including a downwardly converging funnel-shaped bottom with restricted openings to provide a tortuous path for the materials and fuel, beneath the funnel-shaped bottom being supported an outlet 30 valve for drawing off burned material at a regular and regulated rate, without permitting the passage of air therethrough, baffles being employed in the cone supported 35 in a conical bottom to prevent packing of the material in said bottom or the space beneath it, a central supporting pillar being employed in co-operation with the baffles which is likewise supported on the cone and 40 the baffles, the cover having inlets for air for combustion.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of

the invention as expressed in the appended claims.

In the drawings:

Figure 1 is a vertical section of the kiln constructed in accordance with the principles 55 of my invention,

Figure 1^a is a vertical section of the upper part of the kiln forming a continuation of the section shown in Figure 1,

Figure 2 is a vertical section taken along 60 the line 2-2 of Figure 5,

Figure 3 is a vertical section of the charging hopper detached from the kiln,

Figure 4 is a plan view of the hopper shown in Figure 3,

Figure 5 is a horizontal section taken along 65 the line 5-5 of Figure 2,

Figure 6 is a horizontal section taken along the line 6-6 of Figure 2,

Figure 7 is a horizontal section taken along 70 the line 7-7 of Figure 2,

Figure 8 is a plan view of the air nozzle and plates shown in Figure 2,

Figure 9 is a fragmentary vertical section taken along the line 9-9 of Figure 8,

Figure 10 is a vertical section taken along 75 the line 10-10 of Figure 8,

Figure 11 is a vertical section taken along the line 11-11 of Figure 8,

Figure 12 is a fragmentary enlarged vertical section of an upper plate of the valve construction which houses the revolving wiper arm,

Figure 13 is a horizontal section taken 80 along the line 13-13 of Figure 2, and

Figure 14 is a vertical section taken along 85 the line 14-14 of Figure 5.

Referring more particularly to Figure 1 of the drawings it will be seen that a view in elevation of the entire structure is disclosed which is completed by Fig. 1^a. The kiln per se consists of an outer metallic shell 20 having an inner lining 21 formed of fire-resistant material of well known construction and the shell and inner lining rests upon a foundation 22 formed of concrete or other suitable material and this foundation includes a discharge chamber 23.

The exterior of the kiln is provided with the usual balconies 26 located at various hor-

95

100

izontal levels which are reached by means of stairways 27.

An inclined framework, generally designated by the numeral 28, is supported at its 5 lower end in a pit 29 while at the upper end, as shown at 30, it is connected with a post 31 secured to the top of the kiln. This framework is further braced by certain of the balconies which extend laterally from the 10 kiln. The framework supports traveling carriers 32 which are driven by means of a drum or pulley 33 which is revolved by means of a chain or belt 34 driven in turn by a pulley 33^a. An electric motor 35 drives the 15 pulley 33^a.

As the materials are carried upwardly by the traveling carrier 32 they are deposited in a continuous and uniform manner into the hopper 36 mounted on top of the kiln. As 20 illustrated more particularly in Figures 3 and 4 this hopper has an upper section 37 formed of sheet metal which has a portion 38 extending beyond the confines of the reduced stack or inlet 39. The lower portion 25 40 of the hopper is riveted or welded to the upper portion and likewise includes a section 41 projecting beyond the confines of the member 39 and is inclined at the same angle to the horizontal as is the bottom portion 42 30 of the upper section 37. The lower section is riveted at 43 to the upper end of the tubular member 39.

As clearly shown in Figure 1^a the inlet 39 is of much smaller diameter than the kiln and 35 it is desirable that material falling through the neck into the kiln shall be distributed in the kiln as regularly as possible and shall not pile up at one side of the kiln higher than at the other side. As the feed takes 40 place at such a rate that the material never fills the inlet 39, the hopper portion 40 is so shaped that material entering it at one side through the chute 38 will distribute itself so as to fall into the inlet 39 all around the 45 inner circumference thereof. This is accomplished by making the diameter of the curved portion 37 and that of the upper portion 40 and the width of the hopper 36 and portion 38 greater than the diameter of the top of the 50 inlet 39, thus providing a sloping offset in the lower portion 40 of the hopper, indicated at 40°, whereby the material falls into the lower section from around its circumference when the feed takes place at normal rate.

Referring more particularly to Figures 1 and 2, it will be seen that a cylindrical air nozzle 50 is provided within the kiln above the discharge end of the kiln and is located centrally thereof with the axis of the nozzle 60 being in alignment with the axis of the kiln. This nozzle discharges air radially, for combustion purposes, through discharge passages 56 in its circumference, and has an inclined dome-shaped cover 51 upon which rests part 65 of the weight of the materials which are being

burned in the kiln. This cover is subject to an abrasion and is easily replaced. Said cover is removably mounted on the nozzle. A base member 52 formed integrally with the nozzle is bolted to supports running across the top of a cone-shaped discharge member 53. The air nozzle has a central chamber 54 which is adapted to be supplied with air from a conduit 55 illustrated more particularly in Figures 8 and 9 and which will presently be explained. The wall of the nozzle is provided with a plurality of slots 56 through which the air is discharged into the materials of the kiln. A cone-shaped member 57 projects downwardly into the air chamber 54 and is adapted to aid in causing the air to move upwardly and outwardly through the discharge passages 56.

Referring more particularly to Figs. 2, 8, 9, 11 it will be seen that a plurality of castings in the form of baffles 58 of a particular configuration are mounted in the cone-shaped member 53 and are supported thereby. These baffles are connected to a central core 59 and are removable from the cone-shaped discharge member. Each baffle has a down-turned flange 60 and a narrower flange 61 formed at an acute angle to the plate 58. Each baffle includes two sections, as shown in Figure 8, which are substantially triangular in shape with the section 63 having a curved lower edge 64. The flange 61 is sheared off at 65 and engages the cone-shaped discharge member 53 as does the edge 64 of the baffle 58. It is to be noted that these baffles generally 100 are located at an angle to radii passing therethrough so that the upper edge 66 of each baffle is curved and disposed at a tangent to the periphery of the core 59.

The baffle 58^a is modified to the extent that 105 the air conduit 55 is formed integrally with the baffle and is disposed between the angular portion embraced by the baffle and the flange 61. It will be further noted that the conduit extends upwardly through the cone-shaped member 53 and follows a tortuous path at an angle to the radius passing through the baffle 58^a and then extends along a radius as shown at 67 and enters the bottom of the air nozzle 50 and is in communication with the chamber 115 54 of said nozzle.

The upper end of the cone-shaped discharge member 53 is provided with an annular flange 70 which rests upon the members 22 while the lower end is flanged, as shown at 72, in Fig. 2, and is secured to a flange 73 of a connection box 74 which has its upper end in open communication with the lower end of the discharging cone 53. The connection box opens into a distributing box 75 which is secured at its upper end to the junction box and extends beyond the confines of said box. The lower portion of the distributing box is connected to a flanged cover plate 76.

The distributing box, illustrated more par-

ticularly in Figures 1 and 2, has a throttle 77 swingably mounted on a hinge 78 and has a free end 77^a projecting across an opening 80 formed in the top of the plate 76 which I designate as the upper plate. A screw 79 is threaded into a nut 81 and has a swivel connection at 82 with the throttle 77 so that when a hand wheel 79^a is revolved the free end 77^a of the throttle may be moved across the opening 80 in the upper plate 76 and aids in regulating the discharge of the materials from the connection box through the plate.

Referring more particularly to Figures 2, 7, and 12, it will be seen that the upper plate 15 consists of a segment having a downturned flange 76^a connected to an intermediate plate 83, a portion of the upper plate being cut away to provide an opening 80.

A wiper arm 85 is located within the flange 20 portion of the plate 76 and is provided with a hub portion 86 secured to a centrally disposed shaft 87 which is revolved simultaneously with a lower plate 88 which likewise has a hub 89 secured to the shaft 87. The 25 wiper arm as shown in Fig. 7, has a bottom flange 89 which moves over the intermediate plate 83 and across the opening 90 in the intermediate plate. This arm also has a vertically disposed flange 91. The outer free 30 end of the arm has a curved portion 85^a for moving the materials away from the flange 76^a.

The plate 88 has an opening 92 and said plate is revolved by a ring gear 93 formed 35 integrally with the plate 88 and meshes with a spur gear 94 secured to the shaft 95 mounted in an offset housing 96.

The shaft 95 is driven by a gear 97 secured to said shaft. The gear 97 in turn is 40 driven by a gear 98 which is rigid with a motor shaft 99 connected to a motor 100.

The distributing box 75 is provided with a door 101, as shown more particularly in Figures 5 and 14, mounted upon a cup-shaped 45 member 102. A second door 103 is slidably mounted in guides 104 secured to the side wall of the distributing box. The door 101 is held in place by means of bolts 105 and a boss 106 is bolted, at 107, to the door to provide a reduced passage through the door.

A cone-shaped discharge member 53 is provided with a plurality of openings 108 which are closed by doors 109 held in place by cleats 110.

55 A spout 111 is connected adjacent an opening in a housing 112 which includes the lower plate 88. The free end of this spout is adapted to discharge the materials from the housing into a conveyor, screening device, or sizing apparatus as is well known in the art.

A blower 125 is driven by means of a motor 126 and is adapted to supply air under pressure through a conduit 127 to the conduit 60 55 which is in communication with the air

nozzle 50. A branch conduit 114 from the air pipe 127 may lead into pipe 115 which has nozzles 116 for directing air into the body of the kiln at other points than the nozzle 50.

The operation of my device is as follows: The limestone and the fuel are fed into the kiln in practically a continuous stream, in proper proportion to insure a sufficient amount of fuel, when properly burned, to calcine all of the lime, but in no event should there be a considerable excess of fuel. Air for combustion is supplied from below. When the burning is once well under way the rate of combustion within the kiln depends upon the rate of the air supply. While some latitude of this rate is permissible, the rate when the kiln is in actual operation, is maintained practically constant for considerable periods of time. The lime is drawn off from beneath at a rate practically uniform which depends upon the adjustment of the baffle 77 and the speed of rotation of the valve mechanism. The stone and fuel supply, air supply and the rate of withdrawing burned lime are adjusted so as to obtain the most desirable balance between optimum quality of product, optimum of economy of fuel and power and maximum output of the kiln from day to day, suitable changes in adjustment being made as changes take place in the nature or condition of materials or the temperature of the air supplied.

If the baffles and central support with air nozzles were omitted and air supplied only around the periphery of the kiln, as at 116, it would not be practical to withdraw the lime in a satisfactory manner and the withdrawal would not be practically continuous from the entire bottom cross section of the kiln even if it were practicable to burn it properly because the lime would pack in the cone 53 and either not feed at all through 74 or feed downwardly only a core of imperfectly burned material with some unburned fuel. The baffles and central support, with air nozzle, thus assist in making possible uniform speed (a) by partially supporting the weight of the material so that it will not bear downwardly on the valve, (b) by insuring that the downward feed will take place from the entire cross section of the kiln as material is withdrawn from below, and (c) by insuring by a central supply of air that the burning in the central portion of the kiln is adequate before downward feed can take place.

The materials are discharged in a uniform stream through the spout 111 and are treated in a manner which is most suitable for the particular purpose.

The wiper arm 85 moves the materials in a circle, forcing said materials over the openings 90 and 92 so that when said openings align because of the revolving plate 88 said

materials will enter the housing 112 and will be discharged through the spout 111.

Since the arm 85 revolves in synchronism with the plate 88, the speed of rotation of said plate will control the output of the kiln. The speed of rotation of said plate may be varied at will.

I claim:

1. In a lime-kiln, a stack, a fixed discharging cone converging downwardly at the bottom of the stack, a centrally disposed air nozzle in communication with a source of air under pressure, a plurality of fixed curved plates located below the air nozzle and supported by the cone, the inner ends of the plates being disposed off center relative to the nozzle, said plates co-operating with the nozzle for aiding in supporting the materials in the kiln.
2. In a lime kiln, a stack, a discharging apparatus at the bottom of the stack, including a fixed cone converging downwardly for receiving the burning lime, a plurality of plates supported by the cone and inclined at an angle to the vertical, the upper edges of the plates being curved and terminating at their inner ends at points spaced from the axis of the cone, each of said plates being provided with a flange depending from the upper curved edge and having an outer portion engaging the inner wall of the cone, the flange being formed at an acute angle to the plate.
3. In a lime kiln, a stack, a fixed cone converging downwardly at the bottom of the kiln, an air nozzle located centrally of the cone and in communication with the source of air under pressure, said air nozzle being provided with a central chamber, a plurality of slots in the chamber to permit the escape of air, a dome-shaped member at the top of the nozzle, and an inverted conically-shaped member depending from the dome-shaped member and projecting into the air chamber for causing the air to be moved upwardly and at an angle to the horizontal when being discharged through the slots.
4. In a lime kiln, a stack, an inverted discharging cone at the bottom of the stack, a circular air nozzle supported above the cone, a plurality of plates connected together and supported by the walls of the cone, the inner ends of the plates being tangent to a circle defined by the air nozzle, said plate having flanges depending from the upper ends thereof, the plates and flanges co-operating with their air nozzle for aiding in supporting the weight of the materials in the kiln.
5. In a lime kiln, a stack, an inverted discharging cone located at the bottom of the stack, a housing in communication with the lower restricted end of the cone and having an offset portion beyond the communication, a stationary plate having an enlarged opening and forming the bottom of the housing, a second

stationary plate spaced from the first-mentioned plate and having a restricted opening located adjacent the offset portion of the housing, a rotatable plate in contact with the second-mentioned plate and provided with an opening adapted to be aligned with the opening in the second-mentioned plate, and means for rotating the last-mentioned plate.

6. In a lime kiln, a stack, an inverted discharging cone located at the bottom of the stack, a housing in communication with the lower restricted end of the cone and having an offset portion beyond the communication, a stationary plate having an enlarged opening and forming the bottom of the housing, a second stationary plate spaced from the first-mentioned plate and having a restricted opening located adjacent the offset portion of the housing, a rotatable plate in contact with the second-mentioned plate and provided with an opening adapted to be aligned with the opening in the second-mentioned plate, means for rotating the last-mentioned plate, an arm revolved in synchronism with the third-mentioned plate and disposed between the first-mentioned and second-mentioned plates for moving the materials toward the opening in the second-mentioned plate.

7. In a lime kiln, a stack, an inverted discharging cone located at the bottom of the stack, a housing in communication with the lower restricted end of the cone and having an offset portion beyond the communication, a stationary plate having an enlarged opening and forming the bottom of the housing, a second stationary plate spaced from the first-mentioned plate and having a restricted opening located adjacent the offset portion of the housing, a rotatable plate in contact with the second-mentioned plate and provided with an opening adapted to be aligned with the opening in the second-mentioned plate, means for rotating the last-mentioned plate, and means in the inverted cone for aiding in checking the flow of the material through the cone to the housing.

8. In a lime kiln, a stack, an inverted discharging cone located at the bottom of the stack, a housing in communication with the lower restricted end of the cone and having an offset portion beyond the communication, a stationary plate having an enlarged opening and forming the bottom of the housing, a second stationary plate spaced from the first-mentioned plate and having a restricted opening located adjacent the offset portion of the housing, a rotatable plate in contact with the second-mentioned plate and provided with an opening adapted to be aligned with the opening in the second-mentioned plate, means for rotating the last-mentioned plate, a movable baffle located within the housing and adapted to be moved across the

opening in the first-mentioned plate for restricting the flow of materials through the first-mentioned plate onto the second-mentioned plate.

5. 9. In a lime kiln, a stack, an inverted discharge cone located at the bottom of the stack, a housing in communication with the lower restricted end of the cone and having an offset portion beyond the communication, 10 a stationary plate having an enlarged opening and forming the bottom of the housing, a second stationary plate spaced from the first-mentioned plate and having a restricted opening located adjacent the offset portion 15 of the housing, a rotatable plate in contact with the second-mentioned plate and provided with an opening adapted to be aligned with the opening in the second-mentioned plate, means for rotating the last-mentioned 20 plate, a baffle plate hingedly mounted in a vertical plate and having its free end projecting into the housing, means for moving the free end over the enlarged opening in the first-mentioned plate for restricting the 25 flow of materials from the housing onto the second-mentioned plate.

10. In a lime kiln, a stack, an inverted discharging cone at the bottom of the stack, a circular junction box connected with the bottom of the cone, and in communication with said cone, a housing in communication with the junction box having a portion extended beyond the confines of said box and providing an enlarged storage space for the materials 30 passing through the cone and the junction box, a plate for the bottom of the housing and provided with an enlarged opening, a second plate spaced from the first-mentioned plate to form a distributing chamber and provided 35 with a restricted opening adjacent a portion of the opening in the first-mentioned plate, an arm movable in the distributing chamber and over the second-mentioned plate for moving the materials in said chamber towards 40 the opening in the second-mentioned plate, a rotatable plate located below the first-mentioned plate and provided with an opening adapted to be aligned with the opening in the second-mentioned plate, and means for rotating the arm and the third-mentioned plate.

45 11. In a lime kiln, a stack, an inverted discharging cone at the bottom of the stack, a circular junction box connected with the bottom of the cone and in communication 50 with said cone, a housing in communication with the junction box having a portion extended beyond the confines of said box to provide an enlarged storage space for the materials passing through the cone and the junction box, a plate for the bottom of the housing, and provided with an enlarged opening, a second plate spaced from the first-mentioned plate to form a distributing chamber and provided with a restricted opening adjacent a portion of the opening in the first-men-

tioned plate, an arm movable in the distributing chamber and over the first-mentioned plate for moving the materials in said chamber towards the opening in the second-mentioned plate, a rotatable plate located below the first-mentioned plate and provided with an opening adapted to be aligned with the opening in the second-mentioned plate, means for rotating the arm and the third-mentioned plate, and means located in the cone 70 for checking the flow of materials from the kiln to the housing. 75
